Primary Examiner — Angela J Lee(74) *Attorney, Agent, or Firm* — Womble Carlyle Sandridge & Rice, LLP(57) **CLAIM**

I claim the ornamental design for a computer support, as shown and described.

DESCRIPTION

FIG. 1 is a top front right perspective view of my new design;

FIG. 2 is a top rear left perspective view thereof;

FIG. 3 is a front view thereof;

FIG. 4 is a rear view thereof;

FIG. 5 is a left side view thereof; and,

FIG. 6 is a top cross section view taken at line 6-6 in FIG. 5.

The views of the computer support not shown form no part of the claimed design. The dash-dot lines in the figures show unclaimed features and unclaimed environmental elements. The dash-dot lines represent unclaimed boundaries of the claimed design. The use of a separation and a bracket are included to disclaim the particular length of the bracketed element.
